UNITED STATES PATENT OFFICE.

DANIEL WERTZ, OF TOLEDO, OHIO.

HOSE OR GARMENT SUPPORTER.

1,072,542.

Specification of Letters Patent.

Patented Sept. 9, 1913.

Application filed April 4, 1912. Serial No. 688,520.

To all whom it may concern:

Be it known that I, DANIEL WERTZ, a citizen of the United States, and a resident of Toledo, in the county of Lucas and State of Ohio, have invented a certain new and useful Hose or Garment Supporter; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 My invention relates to garment supporters of the kind particularly intended for use in supporting hose and stockings, but is not restricted to such use as it may be used in any connection for which it is adapted 20 or appropriate.

The object of my invention is the provision of an improved article of this character, which is simple, strong and durable in its construction, inexpensive of manufacture, 25 and easy and rapid to engage with a garment, and which is adapted to firmly hold a garment engaged thereto without liability of tearing.

Further objects will be apparent from the 30 following detailed description.

The invention is fully described in the following specification, and while, in its broader aspect, it is capable of embodiment in numerous forms within the scope of the 35 appended claims, a preferred embodiment thereof is illustrated in the accompanying drawings, in which—

Figures 1 and 2 are front and side views of a supporter embodying the features of 40 the invention, with the parts in open position for receiving a garment. Figs. 3 and 4 are similar views thereof, respectively, with the movable clamping member partly moved to garment clamping position, and 45 Figs. 5 and 6 are similar views of a supporter clamped to a garment.

Referring to the drawings, 1 designates the body member of my supporter, and comprises what may be termed the fixed clamping member thereof. This member is preferably composed of wire formed into U-shape with its legs in looped engagement with or otherwise suitably attached to a rigid connecting part 2, and has its legs 50 preferably given a single coil adjacent to their upper ends, as at 3, to provide oppos-

ing bearing openings for the ends of a lever member 4, as hereinafter described. The connecting part 2 for the upper leg ends of the body member 1 is preferably provided with a slot 5 to facilitate the attaching of a suspending strap 6 thereto as indicated. The lever member 4 of the supporter is also preferably formed substantially in U-shape of wire and has each leg coiled in opposite relation, as at 7, to provide bearings for the inner end of the movable clamping tongue or member 8, as hereinafter more fully described. The legs of the lever member 4, after forming the coils 7, extend 60 therefrom preferably at quite a decided angle to the body or looped end portion of the lever member, as best shown in Figs. 2 and 4, and have their terminals bent outward in axial alinement to form trunnions 65 for loosely fitting into the bearing loops 3 of the body member 1, as shown. The movable clamping-tongue or member 8 is also preferably formed of wire which is centrally looped upon itself with legs converging, as at 9, to form an enlarged outer 70 end portion or head, and thence extending inwardly from the head and gradually tapering outwardly, as at 10, with their ends bent outward in axial relation and fitted into 75 respective ones of the bearing openings 80 formed by the coils 7 of the lever member. It is thus apparent that the tongue 8 is carried for free pivotal movements by the lever member 4 and is adapted to work 85 through the outer looped end portion of the body or clamping member 1 when guided or pressed inward for such purpose and the lever 4 swung downward from the elevated position shown in Figs. 1 and 2. 95

In the use of my improved supporter, the parts are first placed in substantially the positions shown in Figs. 1 and 2 with a portion of the garment or article to be supported disposed between the looped portions of the 100 members 1 and 8. The operator then presses the free end portion of the tongue 8 down through the loop of the member 1 and at the same time forces the lever member 4 forward and downward from the elevated position 105 shown in Figs. 1 and 2, to force the tongue downward at the rear of the looped end of the clamping member 1, the engaged portion of the article, which is designated 11 in Figs. 5 and 6, being carried thereby through the 110 loop on the member 1 and downward to the rear of its end, as shown. When the tongue

8 is in such clamping position the looped end portion of the lever 4 projects downward over the outer side of the looped end of the member 1 in opposition to the tongue 8 with 5 its bearing coils 7 interposed between the legs of the member 1 below or in advance of the lever fulcrum, as shown in Figs. 5 and 6. The drawing of the engaged goods through the looped end of the member 1 and downward to the rear thereof by the tongue 8 serves to firmly clamp such cloth to the supporter, and such clamping engagement is augmented by the engagement of the cloth over the shoulders 9 of the tongue 8. When 15 the parts are in article clamping relation, the angle of the lever 4 causes the tongue bearing 7 to project below or to the rear of the lever pivot 3 so that an upward pull exerted by the engaged article upon the tongue 20 would tend to more firmly clamp the parts rather than to impart a releasing movement to the tongue. This is quite an important feature in the construction of the supporter, as otherwise an outward pull upon the engaged article would tend to throw the tongue and lever to article releasing position. To 25 release the clamping engagement of the supporter it is only necessary to swing the control lever 4 to its elevated position, the tongue being thereby drawn from its goods holding position within the body loop 1.

It is evident that the connecting of the body, lever and tongue members in the manner shown and described enables such parts 35 to be easily and quickly assembled, and when assembled to provide a strong and durable supporter, as the journal ends of the lever 4 spring outward into the body member bearings 3, the journal ends of the tongue 8 40 spring outward into the lever bearings 7 and the legs of tongue 8 laterally abut at the inner ends of the shoulders 9 to resist a lateral compression of the supporter and a separation of the parts. While the laterally abutting 45 portions of the tongue 8 strengthen all of the parts against inward compressing stresses, the bar 2 prevents an outward separation of the parts. These features are of considerable value in the construction of a 50 commercially practical article of this class. It is found in practice that this form of supporter is capable of being easily and quickly applied to an article to be supported thereby, and will firmly hold such article against disengagement without liability of tearing the 55 same.

I wish it understood that my invention is not limited to any specific construction or arrangement of the parts except in so far as 60 such limitations are specified in the claims.

Having thus described my invention, what I claim as new and desire to secure by Letters Patent, is,—

1. A garment supporter comprising a U-shaped wire body member having its legs

coiled to form axially registering pintle bearings in advance of the plane of said legs, means connecting the free ends of the legs without such bearings, a looped wire lever having the ends of its legs bent laterally to form pintles for fitting into the bearings of the body member, the lever legs being coiled intermediate their ends to form axially registering pintle bearings which, when the lever is in clamped position, are projected through the body to the rear of the lever fulcrum, and a tongue pivoted at its inner end to the lever bearings and adapted to project through the body member and to the rear of its lower end when the lever is in clamped position, substantially as described. 75

2. A garment supporter, comprising a U-shaped wire body member the legs of which are coiled to form bearings between the ends thereof, a bar connecting the free ends of the legs without said bearings, a U-shaped wire lever having its legs looped between their ends to form opposing bearings and then extending at an angle with relation to the outer looped end portion of the lever 85 and having their free ends bent laterally and journaled in the body member bearings, a looped wire tongue having its legs bent laterally and journaled in the bearings of said lever legs, the outer looped end of 90 said tongue being adapted to be projected through and beyond the looped end of the body member in the general direction of projection thereof to coöperate therewith in clamping an article, and said lever having 95 its outer end of a length to bear against the outer side of the looped end of the body member in opposition to the tongue when the parts are in clamped position, the inner angled ends of the lever legs causing the 100 tongue-bearings thereof to be projected to the rear of the member bearings when the tongue is in clamped position whereby an end thrust on the tongue will tend to tighten it against the body loop. 110

3. A garment supporter, comprising a U-shaped wire body member having its legs coiled to provide opposing bearings, a U-shaped wire lever member having the free ends of its legs bent laterally and journaled in said bearings, said lever being adapted to bear at its looped end against the side of the looped end of the body member when the parts are in clamped position, the legs of said lever being provided between their 115 ends with bearings, and a looped wire tongue the free ends of the legs of which are bent laterally and journaled in the bearings of said lever, said tongue being adapted to have its free end projected through and to the rear of the looped end of the body member in opposition to the outer end of the lever when the parts are in clamped position, said lever being angled 120 to project the tongue bearings thereof 125 130

through the body member when the parts are in clamped position to dispose the body member bearings in advance of the line of longitudinal thrust of the tongue.

- 5 4. A garment supporter comprising a looped body member having its legs coiled to provide opposing bearings, a looped lever member having the free ends of its legs provided with laterally projecting journals 10 which are sprung outward into the body member bearings, and having opposing bearings provided on its legs, a looped tongue member having the free ends of its legs provided with laterally projecting journals 15 and sprung outward into the lever bearings, and means connecting the free ends of the legs of the body member for preventing an outward springing of such legs.
5. A garment supporter comprising a 20 looped wire body member having its legs coiled to provide opposing bearings, a bar

connecting the outer ends of said legs, a looped wire lever member having the ends of its legs bent outward and sprung into said body member bearings and provided 25 between their ends with bearings, and a looped wire tongue having the free ends of its legs bent outward and sprung into the lever bearings and having its legs laterally abutting between the end portions thereof 30 at a point removed from the bent ends to resist an inward springing of the legs, said tongue and lever being adapted to cooperate with the body member to hold an engaged article. 35

In testimony whereof, I have hereunto signed my name to this specification in the presence of two subscribing witnesses.

DANIEL WERTZ.
